VEHICLE ROOM AND BERTH
ARRANGEMENTBasil E. Jones, Flossmoor, Ill., assignor to The
Pullman Company, Chicago, Ill., a corporation
of Illinois

Application October 26, 1945, Serial No. 624,641

9 Claims. (Cl. 105—315)

1

This invention relates to railway sleeping cars and has particular reference to that type of such cars utilizing rooms adapted for the accommodation of two or more passengers in each room. The invention has for its primary object, so to arrange the various accommodations in a room of the type referred to as to provide the greatest convenience to the occupants and ease of access to the individual accommodations while affording the most space in the room, and the utilization of such space to the utmost comfort of the occupants during both day and night use of the room.

One object of the invention resides in the provision of a room adapted to have communication with an adjoining room and wherein the toilet facilities for the room are separated to provide fixtures at opposite sides of a communicating door at one side of the room with a wardrobe disposed above one fixture and a diagonally arranged mirror over the other, and having a convertible sofa at the opposite side of the room with a foldable upper berth overlying the sofa and provided with an entrance door located in another wall between the sofa and one of said fixtures.

An important object of the invention comprises the provision of a new upper berth arrangement disposed, when closed, in a vertical plane substantially flush with the sofa backrest and with the surrounding wall areas and having counterbalancing mechanism disposed entirely outside the area of the bunk at opposite ends, operatively connected with the bunk but concealed from view.

The foregoing and other and more specific objects of the invention are attained in the room arrangement illustrated in the accompanying drawings, in which:

Fig. 1 is a perspective drawing showing a general view of a room arranged and equipped in accordance with the present invention, having a covered washbasin disposed in one corner of the room at the side wall of the vehicle with a lighted mirror diagonally arranged in the corner above the basin and having an enclosed hopper arrangement disposed in an inside corner of the room at the opposite side of a communicating door to an adjoining room, with a wardrobe disposed in the corner above the hopper mechanism and having a convertible sofa and an upper berth adapted for operative disposition in parallel overlying relationship along the wall opposite to the toilet fixtures, and having an entrance door between the sofa and the hopper fixture and a

window in the side wall between the sofa and washbasin;

Fig. 2 is a general plan view of the room, clearly revealing the relative disposition of the various fixtures and accommodations in the room and showing the sofa ready for daytime use disposed along one side of the room with the toilet fixtures in opposite corners at the other side and having an entrance door and a window in the respective other walls;

Fig. 3 is a transverse sectional view taken on the line 3—3 of Fig. 2 illustrating that side of the room opposite the communicating door and toilet fixtures and showing the upper berth in closed position, flush with contiguous wall areas, and the convertible sofa with its backrest in upright daytime seating position and showing a side aisle which extends longitudinally of the vehicle at one side of the room;

Fig. 4 is a perspective view of that side of the room illustrated in Fig. 3 but showing the upper and lower berths made up for night occupancy with the convertible backrest of the sofa lowered to horizontal position to provide a bed and the upper berth opened to a position providing a bed at that level with detachable safety guards extending between the open side of the bunk and the ceiling and showing the strut members engageable with the respective side walls for supporting the berth in open position and maintaining that position against the action of the counterbalancing mechanism, the flexible connection to which is revealed at each end of the bunk;

Fig. 5 is a longitudinal sectional view of the room taken on the line 5—5 of Fig. 2 looking at the aisle partition and showing the convertible sofa in daytime position at one side of the entrance door with the upper berth closed and the wardrobe and enclosed hopper arrangement at the opposite side of the entrance door; and

Fig. 6 also is a longitudinal sectional view of the room taken on the line 6—6 of Fig. 2 but looking at the side wall of the vehicle and showing the upper berth and convertible sofa made up ready for night occupancy with the window in the side wall disposed between these accommodations and the covered washbasin at the other side of the room, and showing the angularly disposed mirror above the basin.

The room illustrated comprises what is known as a Pullman "compartment" but certain features of the invention shown as applied in a room of this type may be utilized also in other accommodations, such, for instance, as a "drawing room" or a "bedroom," without departing from the in-

vention. In the drawings 10 represents a railway vehicle having a roof 11, a floor 12, side walls 13 and 14 and a longitudinally extending partition 15 spaced from the wall 14 to define an aisle 16 extending lengthwise of the vehicle between a vestibule (not shown) at one end of the vehicle and the other end thereof and communicating with a plurality of individual rooms disposed between the aisle wall 15 and the side wall 13. Transverse partitions 17 and 18 extending between side wall 13 and aisle partition 15 define therewith a room having a ceiling 19 spaced downwardly from the roof 11 to provide space for an air duct 20 extending longitudinally of the vehicle and connected with the room by means of branch duct 21 opening through the ceiling 19 to withdraw vitiated air from the room by means of equipment (not shown) located in an end zone of the vehicle. A ceiling 22 over the aisle 16 provides space thereabove for a duct 23 disposed outside the plane of aisle partition 15 and adapted to supply conditioned air to the room from air conditioning equipment (not shown) located in an end zone of the vehicle. A branch duct 24 leads from the main supply duct 23 and communicates with the room through ceiling 19 by means of a suitable type of register for controlling the inlet of conditioned air.

An entrance door 26 in the aisle partition 15 affords communication with the room from the aisle 16 and a ventilator 27 in this door provides for the recirculation of air from the room through the aisle to a return air grille at that end of the vehicle containing the air conditioning equipment referred to. A window 28 for the room is disposed in side wall 13, and since the room is adapted to be used in intercommunicating relation with an adjoining room, the cross partition 17 is provided with a door 29 to permit of the use of the room ensuite with the next adjacent room. At one side of the communicating door between the rooms in the corner of the cross partition 17 and aisle partition 15 and to one side of the entrance door 26, a wardrobe 31 is provided for the accommodation of articles of wearing apparel of the occupants of the room. The wardrobe is provided with a door 32 affording access to clothing hung therein, and a latch 33 is adapted releasably to maintain the door in closed position. A support rail 34 (see Fig. 5) provides a convenient means of hanging wearing apparel in the wardrobe by means of the usual clothes hangers. A full length mirror 36 is mounted upon the inner side of entrance door 26 convenient to users of the wardrobe, and a mirror 41 is provided at the other side of the wardrobe on the communicating door 29.

Immediately beneath the wardrobe proper, a tilting hopper arrangement 37 is provided which is adapted to be moved from the operative position indicated in dotted lines in Fig. 2 to a tilted or folded position partially enclosed by the lower portion of the wardrobe cabinet, and which enclosure is completed by the hinged actuating door 38, which upon opening and closing automatically moves the hopper between operative and inoperative positions respectively. The door 38 is hinged at that side of the hopper mechanism adjacent the aisle partition 15 so that when in operative position the hopper 37 is readily accessible from the opposite or room side. When the door 38 is open, it occupies such a position substantially parallel to the plane of the aisle partition as to block the entrance door 26 and effectively prevent its being opened when the hopper 37 is

disposed in operative position. The handle 39 on the actuating door 38 is disposed below the level of the mirror 36 on the entrance door so that it cannot possibly come in contact with the mirror should the entrance door be tried while the door 38 is open.

At the other side of the communicating door 29, a fixed washbasin 42 is disposed in the corner of the side wall 13 and cross partition 17 at one side of the window 28. The washbasin is rigidly mounted in operative position and normally is concealed by a hinged cover 43 which in its lowered position fits about the faucet assembly 44 covering the actuating handles to render them inoperative in this position of the cover, and when the cover is raised, the faucet assembly, including the handles, is fully exposed for normal operation. The under side of the cover 43 is of metal to match that of the basin, and the upper surface is finished to match splash shields 46 and 47 on the side wall and cross partition immediately adjacent to the washbasin. The cover is hinged at 48 to swing to a vertical position against the side wall where it is releasably maintained by spring pressed catch 49 mounted upon the cross partition in position to engage the cover as it is moved to open position. A removable cover plate 51 on the side finish beneath the basin permits access to the drain mechanism for service and maintenance operations. A hinged door 52 affords access to a clean towel compartment convenient to the basin. Above the basin a mirror 53 is disposed at a convenient angle for use diagonally across the corner between side wall 13 and partition 17. A lower horizontal lighting fixture 54 and an upper fixture 56 having downwardly directed twin lenses provide illumination for users of the mirror. In this same corner of the room, above the level of the mirror, an overhead L-shaped luggage rack 57 is supported from the side wall 13 and cross partition 17 by means of brackets 58 and 59 respectively, for the accommodation of articles placed thereon by the occupants of the room.

Beneath the window 28, throughout the extent of side wall 13 within the room, the side finish or wainscoting 61, as best shown in Figs. 3 and 4, is spaced a substantial distance inwardly from the side wall structure to provide for a heating system. The wainscoting is spaced from the floor as 50 at 62 to provide an opening for the passage of air. The space between the wainscoting and side wall structure 13 is closed at the window sill position by a capping 63 disposed on a level with the surface of cover 43 overlying the washbasin and extending throughout the window area and beyond, as shown in Fig. 4. A sloping plate 64 (see Fig. 3) separates the space behind the wainscoting into an upper chamber 66 and a passage 67 having a restricted outlet opening 68 in the immediate vicinity of window 28. The plate 64 is disposed at an angle such as to provide a passage having a width at the bottom of substantially the full area between the panel 61 and the side wall 13, but approaching the side wall at the window sill to 65 provide a very restricted emission opening immediately adjacent the window. The function of the passage 67 is to provide a sheet of warm air over the entire area of window 28 to prevent the radiation of cold air therefrom into the room to the discomfort of passengers. Air drawn from the room through opening 62 at the floor passes over finned heating pipes 69 and enters passage 67 which acts somewhat as a chimney, creating a positive circulation of air through the opening 75 62, over the heating pipes 69, through the pas-

sage 67, and ejected through the outlet 68 in the form of a continuous jet providing a heated curtain of air over the entire window area to prevent any possibility of persons in the room being conscious of the cold air normally emanating from a window of the size of that shown. The sloping plate 64 is provided with a series of horizontally aligned openings 71 and an associated louvered shutter member 72 slidably mounted in guides 73 provides a means of adjusting the openings to control the amount of heated air passing into the chamber 66 through the openings. This adjustment is made initially at the time of installation in accordance with requirements necessary to the proper heating of the room and it is not necessary for the adjustment to be disturbed in the normal use of the arrangement thereafter. Admission of heated air from the passage 67 into the chamber 66 serves to heat the wainscoting 61, which acts as a radiant heating panel to maintain the temperature of the room at a normal comfortable level without drafts.

The room is designed for accommodation of two passengers, with provision for individual sleeping accommodations, and adapted to provide comfortable daytime seating arrangements for both persons. These facilities comprise a convertible sofa 76 and a foldable berth 77 disposed adjacent the cross partition 18 at the other side of window 28 and entrance door 26 from the toilet facilities hereinbefore described. The sofa includes a seat portion 78 extending substantially full length of the room from the aisle partition 15 to the side finish 61 and which is supported at this latter position on an angle member 79 secured to the side finish and at the aisle partition on a structure including shoe box 81 having hinged access doors 82 and 83 opening, respectively, inside the room and from the aisle. The backrest 84 for the sofa is convertible from the upright daytime position illustrated in Fig. 5 to the inverted horizontal nighttime position illustrated in Fig. 6. The backrest is pivotally mounted for movement between these two positions and includes a frame 86 upon which the backrest cushion 84 is mounted. This frame 84 is provided with trunnion members 87 mounted upon respectively opposite ends of the frame and adapted pivotally to support the backrest in trunnion brackets 88 mounted respectively upon the side finish 61 and aisle partition 15. The backrest is pivotally supported in these brackets 88 for folding movements between day and nighttime operative positions. In the daytime the backrest is locked in upright position by retractable latches actuated by an operating handle 89, and at night when the backrest is converted for sleeping purposes, it is supported in its horizontal inverted position on brackets 91 mounted respectively upon the side finish 61 and aisle partition. The frame 86 is adapted to support a mattress and bedding by means of a flexible base 92 mounted in the frame and providing a resilient support for the mattress 93. In the upright position of the backrest, the bedding is prevented from escaping from the frame 86 by means of a hinged panel 94 pivotally mounted on the lowermost side rail of the frame and having rollers 95 on the free edge thereof adapted to ride up the cross partition 18 as the backrest is pivoted to horizontal position. As best shown in Figs. 4 and 6, the panel prevents the bedding from falling between the bed and the partition 18 in the nighttime position of the backrest as well as

in the daytime position illustrated in Fig. 5. The seat cushion 78 and the backrest cushion 84 are both shaped to provide the most comfortable contours for seating purposes and the backrest is disposed flush with adjoining wall surface 97 which is contoured to match that of the backrest (see Figs. 2, 3 and 4). Lighting fixtures 98 are disposed at respectively opposite ends of the sofa 76 and mounted upon the side wall 13 and aisle partition 15 in positions to provide reading lights for persons seated on the sofa or reclining on the bed when the backrest is converted for the purpose, and including night lighting features for bedtime use. A fixture 95 located on the aisle partition 15 provides general illumination for the room. An ashtray 99 retractably mounted in the side finish 61 is conveniently located to the use of such persons, and table brackets 101 are adapted to receive a removable table which may be inserted for the convenience of seated passengers.

As will be observed from the drawings, particularly Figs. 2, 5 and 6, the length of the room (its dimension in the direction of the length of the car) is approximately twice the width of the sofa 76, or is twice as great as the distance between the partition 18 and the front edge of the sofa. Thus the room includes a standing space, between the front edge of the sofa and the partition 17, approximately as long as the sofa is wide. To make a room of such comparatively small proportions effectively spacious enough for comfortable occupancy by two persons is of course one of the principal objects of the present invention, and this object has been attained by the novel relative arrangement of the several fixtures and facilities which constitutes an important feature of the invention.

The foldable berth 77 when in its closed position is disposed in a vertical plane flush with adjoining wall surfaces 102 on the partition 18 and substantially flush with the general plane of the surface of the sofa backrest 84 so that the utmost spaciousness is provided in the room and the general air of roominess is enhanced by the greater headroom thus afforded, while the undesirability of an upper berth projecting over the sofa in the daytime positions thereof is avoided and the hazard of an overhanging berth over the heads of persons seated on the sofa thereby eliminated. In operative sleeping position the berth is disposed horizontal, in parallel overlying relationship with the converted sofa bed, as best shown in Fig. 4. The berth is received flush with in a recess 103 when in closed position and comprises a bunk 104 having trunnions 106 at respectively opposite ends adapted to be mounted in trunnion brackets 107 in the end walls of the recess 103 for the pivotal support of the bunk during folding movements between open and closed positions. The bunk is provided with a flexible base 108 for resiliently supporting a mattress 109. A bottom guard member 110, mounted upon the partition 18 and shaped to provide a curvature conforming to the arc described by the lower edge of the bunk in its movements between open and closed positions, is disposed at the lower extremity of the recess 103 in position to close the space between the bunk and partition 18 and thereby prevent the escape of bedding in either position of the berth.

In closed position, the bunk 104 is locked by the usual latch rods (not shown) actuated from the keyway 111 by means of a porter's berth key, but in the open horizontal position the bunk is

supported by novel means which act as safety devices to prevent undesired closing of the bunk under influence of counterbalancing mechanism provided to aid in the operation of the berth. As best shown in Figs. 4 and 6, these means comprise strut members 112 pivotally mounted in the bunk at respectively opposite ends on the inner face of the front side wall for movement in a vertical plane, when the bunk is open, from retracted positions in the bunk to operative positions at upward inclinations toward the side wall 13 and aisle partition 15. These members support the free edge of the bunk for sleeping purposes and at the same time prevent it from rising, so that the berth is securely locked in horizontal position. The strut members are each provided with a head portion adapted to be entered into slotted brackets 113 on the side wall and aisle partition where they are securely locked by means of pivotally mounted latch members 114 adapted to be swung to positions overlying the respective head portions and effectively preventing unintentional withdrawal of the strut members. The head portions are each constructed to provide a part interlocking with the respective slotted brackets for supporting the berth and a shouldered portion cooperating with the latch 114 to ensure the retention of the strut members in fully interlocked engagement with the brackets to prevent upward movement of the berth. When the latches 114 are released, the strut members may be swung to inoperative positions in the berth, lying between the mattress 109 and the front rail of the bunk, whereupon the berth may be moved to closed position in the recess 103.

The berth 104 is fully counterbalanced for ease of operation, and the counterbalancing mechanism is fully concealed and disposed entirely outside the area of the berth whereby to preserve the smooth arrangement of the berth flush with the adjoining wall areas and enabling the use of a full length bed without interference from berth supporting rods or chains disposed between the mattress 109 and the end wall of the bunk within the area of the berth. The counterbalancing arrangement includes torsional spring mechanisms 115 mounted at respectively opposite ends of the berth recess 103 and fully enclosed in the spaces behind wall areas 102 outside of the end walls of the bunk and operatively connected with the bunk through the medium of flexible chains 116 extending from the perimeter of the torsional springs through openings 117 in the walls 102. The flexible chains are not fastened directly to the bunk proper, but are pivotally connected to extension plate members 118 secured to the face of the bunk 104 and projecting beyond respectively opposite ends thereof at a point removed from the trunnions 106 about which the bunk pivots and adapted to align with and completely close the openings 117 in wall areas 102 whereby to conceal the counterbalancing mechanism and the connections thereto. The extension plates 118, if desired, may be disposed flush with the surface of the bunk 104 and received flush with the surfaces of walls 102 in closed position. The plates are rigid with the bunk and enable the disposition of the counterbalancing devices entirely outside the area of the bunk. In the open sleeping position of the berth 104, berth safety guards 120 are provided which are fixedly secured at their lower ends in the bunk and extend upwardly therefrom to the ceiling, where they are releasably secured to rigidly mounted catch members 119 which support the

guard members in positions at the outer side of the berth to prevent an occupant of the berth from rolling beyond the edge thereof. The guards are spaced apart at the center of the berth to permit access thereto.

From the foregoing it will be seen that there has been provided a room having a convertible sofa disposed along one wall, with a berth thereabove adapted for disposition in parallel overlying relationship with the converted sofa or foldable to a vertical position flush with adjoining wall areas and with the backrest portion of the sofa in its normal position, and having toilet facilities for the room arranged at the opposite wall and including a fixed concealed washbasin and an enclosed folding hopper disposed respectively at opposite sides of a communicating door for convenient use of either separately, without interference or restriction imposed by the other, 15 and having a diagonally arranged mirror disposed in the corner above the washbasin and a wardrobe in the corner above the folded hopper, with an entrance door to the room between the sofa and the toilet facilities opening through one of 20 the other walls and having a window in the wall opposite the entrance door alongside the sofa and the washbasin.

What is claimed is—

1. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa 30 in the room at one side of the entrance door adjacent one of said cross partitions having a backrest convertible to a bed, a foldable berth above the sofa disposed flush with adjoining wall areas and movable to a position in parallel overlying 35 relationship with said bed, a window in the side wall of the room, a hopper and a washbasin at the other side of the entrance door and window respectively from said sofa adjacent to the other cross partition, standing space between said sofa 40 and said hopper and washbasin, said last-named partition having a communicating door therein, said basin and hopper being disposed at opposite sides of the communicating door adjacent to the side wall and the aisle partition respectively, and 45 a wardrobe in the corner of the room with said hopper and disposed above the level of the hopper, said room being of a width defined substantially by the length of said sofa and of a length substantially equal to twice the width of the sofa.
5. 2. In a vehicle having side walls and a partition spaced from one of the side walls defining a longitudinal side aisle, spaced parallel cross partitions extending from the aisle partition to the other side wall defining a room, an entrance door to the room located in the aisle partition, a convertible sofa in the room at one side of the entrance door adjacent one of said cross partitions, a window in the side wall of the room, a hopper and a washbasin at the other side of the 50 entrance door and window respectively from said sofa adjacent to the other cross partition, standing space between said sofa and said hopper and washbasin, said last-named partition having a communicating door therein, said basin and hopper being disposed at opposite sides of the communicating door adjacent to the side wall and the aisle partition respectively, and a wardrobe in the corner of the room with said hopper and disposed above the level of the hopper, said room being of a width defined substantially by the length of said sofa and of a length substantially equal to twice the width of the sofa.
6. 3. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa 55 in the room at one side of the entrance door adjacent one of said cross partitions, a window in the side wall of the room, a hopper and a washbasin at the other side of the entrance door and window respectively from said sofa adjacent to the other cross partition, standing space between said sofa and said hopper and washbasin, said last-named partition having a communicating door therein, said basin and hopper being disposed at opposite sides of the communicating door adjacent to the side wall and the aisle partition respectively, and a wardrobe in the corner of the room with said hopper and disposed above the level of the hopper, said room 60 being of a width defined substantially by the length of said sofa and of a length substantially equal to twice the width of the sofa.
7. 4. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa in the room at one side of the entrance door adjacent one of said cross partitions, a window in the side wall of the room, a hopper and a washbasin at the other side of the entrance door and window respectively from said sofa adjacent to the other cross partition, standing space between said sofa and said hopper and washbasin, said last-named partition having a communicating door therein, said basin and hopper being disposed at opposite sides of the communicating door adjacent to the side wall and the aisle partition respectively, and a wardrobe in the corner of the room with said hopper and disposed above the level of the hopper, said room 65 being of a width defined substantially by the length of said sofa and of a length substantially equal to twice the width of the sofa.
8. 5. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa in the room at one side of the entrance door adjacent one of said cross partitions, a window in the side wall of the room, a hopper and a washbasin at the other side of the entrance door and window respectively from said sofa adjacent to the other cross partition, standing space between said sofa and said hopper and washbasin, said last-named partition having a communicating door therein, said basin and hopper being disposed at opposite sides of the communicating door adjacent to the side wall and the aisle partition respectively, and a wardrobe in the corner of the room with said hopper and disposed above the level of the hopper, said room 70 being of a width defined substantially by the length of said sofa and of a length substantially equal to twice the width of the sofa.
9. 6. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa in the room at one side of the entrance door adjacent one of said cross partitions, a window in the side wall of the room, a hopper and a washbasin at the other side of the entrance door and window respectively from said sofa adjacent to the other cross partition, standing space between said sofa and said hopper and washbasin, said last-named partition having a communicating door therein, said basin and hopper being disposed at opposite sides of the communicating door adjacent to the side wall and the aisle partition respectively, and a wardrobe in the corner of the room with said hopper and disposed above the level of the hopper, said room 75 being of a width defined substantially by the length of said sofa and of a length substantially equal to twice the width of the sofa.

length of said sofa and of a length substantially equal to twice the width of the sofa.

3. In a vehicle having side walls and a partition spaced from one of the side walls defining a longitudinal side aisle, spaced parallel cross partitions extending from the aisle partition to the other side wall defining a room, an entrance door to the room located in the aisle partition, a convertible sofa in the room at one side of the entrance door adjacent one of said cross partitions, a window in the side wall of the room, a hopper and a washbasin at the other side of the entrance door and window respectively from said sofa adjacent to the other cross partition, and standing space between said sofa and said hopper and washbasin, said last-named partition having a communicating door therein, and said basin and hopper being disposed at opposite sides of the communicating door adjacent to the side wall and the aisle partition respectively, said room being of a width defined substantially by the length of said sofa and of a length substantially equal to twice the width of the sofa.

4. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa in the room at one side of the entrance door adjacent one of said cross partitions having a backrest convertible to a bed, a foldable berth above the sofa disposed flush with adjoining wall areas and movable to a position in parallel overlying relationship with said bed, a window in the side wall of the room, a hopper and a washbasin at the other side of the entrance door and window respectively from said sofa adjacent to the other cross partition, and standing space between said sofa and said hopper and washbasin, said last-named partition having a communicating door therein, and said basin and hopper being disposed at opposite sides of the communicating door adjacent to the side wall and the aisle partition respectively, said room being of a width defined substantially by the length of said sofa and of a length substantially equal to twice the width of the sofa.

5. In a vehicle having side walls and a partition spaced from one of the side walls defining a longitudinal side aisle, spaced parallel cross partitions extending from the aisle partition to the other side wall defining a room, an entrance door to the room located in the aisle partition, a sofa in the room at one side of the entrance door adjacent one of said cross partitions having a backrest convertible to a bed, a foldable berth above the sofa disposed flush with adjoining wall areas and movable to a position in parallel overlying relationship with said bed, a window in the side wall of the room, a hopper and a washbasin at the other side of the entrance door and window respectively from said sofa adjacent to the other cross partition, and standing space between said sofa and said hopper and washbasin, said basin and said hopper being disposed at opposite sides of the room adjacent the side wall and the aisle partition respectively whereby such facilities are entirely separate and independent of each other, said room being of a width defined substantially by the length of said sofa and of a length substantially equal to twice the width of the sofa.

6. In a vehicle having side walls and a partition spaced from one of the side walls defining a longitudinal side aisle, spaced parallel cross par-

titions extending from the aisle partition to the other side wall defining a room, an entrance door to the room located in the aisle partition, a sofa in the room at one side of the entrance door adjacent one of said cross partitions, a window in the side wall of the room at the side of the sofa, a hopper and a washbasin at the other side of the entrance door and window respectively from said sofa adjacent to the other cross partition, and standing space between said sofa and said hopper and washbasin, said basin and said hopper being disposed at opposite sides of the room adjacent the side wall and the aisle partition respectively whereby such facilities are entirely separate and independent of each other, said room being of a width defined substantially by the length of said sofa and of a length substantially equal to twice the width of the sofa.

7. In a vehicle having side walls and a partition spaced from one of the side walls to define a longitudinal side aisle, spaced parallel cross partitions extending from the aisle partition to the other side wall defining a room, an entrance door to the room located in the aisle partition, a sofa in the room at one side of the entrance door adjacent one of said cross partitions having a backrest convertible to a bed, a foldable berth above the sofa disposed flush with adjoining wall areas and movable to a position in parallel overlying relationship with said bed, a hopper and a washbasin at the other side of the entrance door from said sofa adjacent to the other cross partition, and standing space between said sofa and said hopper and washbasin, said basin and said hopper being disposed at opposite sides of the room adjacent the side wall and the aisle partition respectively whereby such facilities are entirely separate and independent of each other, said room being of a width defined substantially by the length of said sofa and of a length substantially equal to twice the width of the sofa.

8. In a vehicle having side walls and a partition spaced from one of the side walls to define a longitudinal side aisle, spaced parallel cross partitions extending from the aisle partition to the other side wall defining a room, a sofa in the room at one side adjacent to one of said cross partitions and having a backrest convertible to a bed, a foldable berth above the sofa disposed flush with adjoining wall areas and movable to a position in parallel overlying relationship with said bed, a hopper and a washbasin at the other side of the room from said sofa adjacent to the other cross partition, and standing space between said sofa and said hopper and washbasin, said basin and said hopper being disposed at opposite sides of the room adjacent the side wall and aisle partition respectively whereby such facilities are entirely separate and independent of each other, said room being of a width defined substantially by the length of said sofa and of a length substantially equal to twice the width of the sofa.

9. In a vehicle having side walls and a partition spaced from one of the side walls to define a longitudinal side aisle, spaced parallel cross partitions extending from the aisle partition to the other side wall defining a room, a sofa in the room at one side adjacent to one of said cross partitions, a hopper and a washbasin at the other side of the room from said sofa adjacent to the other cross partition, and standing space between said sofa and said hopper and washbasin, said basin and said hopper being disposed at opposite sides of the room adjacent the side wall and aisle partition respectively whereby such facilities are

11

entirely separate and independent of each other, said room being of a width defined substantially by the length of said sofa and of a length substantially equal to twice the width of the sofa.
